[57] CLAIM

The ornamental design for a combined broom and implement for removing dust, as shown and described.

DESCRIPTION

FIG. 1 is an exploded perspective view of the combined broom and implement for removing dust embodying the design of the present invention;

FIG. 2 is a front elevational view thereof shown in assembled condition, the rear being a mirror image of the front shown in FIG. 2;

FIG. 3 is a side elevational view thereof, the side opposite being a mirror image of the side shown in FIG. 3;

FIG. 4 is an end elevational view thereof; and,

FIG. 5 is an end elevational view thereof.

FIG. 2

FIG. 3
